UNITED STATES PATENT OFFICE.

EDWIN FITTS, OF DETROIT, MICHIGAN. ASSIGNOR TO DETROIT STOKER COMPANY, OF DETROIT, MICHIGAN, A CORPORATION OF MICHIGAN.

FURNACE.

1,329,891.

Specification of Letters Patent.

Patented Feb. 3, 1920.

Application filed May 27, 1916. Serial No. 100,412.

To all whom it may concern:

Be it known that I, EDWIN FITTS, a citizen of the United States of America, residing at Detroit, in the county of Wayne and 5 State of Michigan, have invented certain new and useful Improvements in Furnaces, of which the following is a specification, reference being had therein to the accompanying drawings.

10 This invention relates to furnaces and refers more particularly to improvements in furnaces of the type which are provided with side feed stokers.

In some furnaces of this general class a 15 flat arch member is employed and it is among the objects of the invention to provide a new and improved arrangement for supporting the flat arch member. Other objects of the invention are to provide a 20 construction in which the arch member is supported on the stoker side plate, the latter being preferably constructed in sections so that the height of the arch member can be varied in accordance with the 25 size and shape of the furnace; to provide a construction in which this extension feature is maintained while permitting of a standardized lower section for the side plate, thus permitting the use of the same lower 30 section for various sizes of furnaces; to provide an improved construction for supporting the protecting blocks for the air twy whole; to provide a construction in which there is a vertical wall arrangement for 35 protecting the air twy whole and side plates from the heat of the furnace, this wall being preferably also supported from the stoker side plate; to provide a construction in which the protecting blocks are independently removable for repair or renewal 40 but in which the blocks are locked from displacement when in use and normally held in vertical alinement with the inner face of the remainder of the vertical side wall; 45 to provide a novel construction and mounting for the upper covering or roof of the arch, and in general to provide an improved furnace construction of the character above referred to.

50 The invention further resides in various features of construction and such arrangements and combinations of parts as will more fully hereinafter appear.

In the drawings:

55 Figure 1 is a partial vertical cross sec-

tion through a furnace embodying my invention;

Fig. 2 is a vertical sectional view taken at right angles to Fig. 1 centrally through one of the hangers.

60 Describing in detail the particular embodiment of my invention shown in the drawings, A designates one of the inclined grates of the furnace, B the combustion chamber and C the refractory arch forming the top of the combustion chamber. This arch is of the type known as "flat arch" formed of a plurality of rows of blocks C', C'', etc., supported from I-beams D by means of cross beams D' and hangers 65 D''. At the lower ends the hangers D'' have yokes D''' to which are secured by bolts D'', the cross beams D', the heads E' of which fit in grooves E'' in the arch blocks so that the latter are suspended from the I-beams D. 70

75 In connection with this type of furnace there is at the side of the combustion chamber a fuel magazine F from which the fuel is fed to the combustion chamber by stokers F'. The inner wall or side plate G of this 80 fuel magazine is utilized as a supporting wall for the ends of the arch supporting beams D, and in addition to supporting the arch, the side plate is in the present construction utilized for carrying a protecting wall H. The latter is preferably 85 vertically arranged and is spaced from the side plate to provide a passage H' which forms a connection between the air twy whole members I and the air space H'' above the 90 arch. In turn, the air twy whole are provided with a series of protecting blocks I' so arranged that their inner faces form substantially a continuation of the inner face of the vertical wall H.

95 The air twy whole members I are preferably formed of a plurality of sections I'' of cast metal, each section having an inclined bottom I''' and vertical ribs I''. The connection 100 between these sections and the side plate is formed by hook members J on the twy whole sections, which engage sockets J' on the side plate G. The support for the vertical wall H comprises a plate member M which extends across and rests upon the top surfaces of the inwardly extending ribs L. The latter are preferably cast integral with the lower section of the side plate, these ribs being spaced a suitable distance apart.

105 For holding the refractory blocks I' in 110

alinement the blocks are provided with recesses M^2 which register with openings M' in the ribs L .

A locking rod N extends through the recesses M^2 and openings M' , and serves to hold the blocks from lateral displacement. Also this locking arrangement permits of the independent removal and replacement of any of the blocks I' , so that in case of repair or renewal it is only necessary to withdraw the rod until it is clear of the particular block to be removed, after which the block can be removed from the supporting member by drawing the same laterally off from the supporting member.

The support for the blocks comprises a plurality of substantially horizontal prongs O projecting inwardly from the lower portion of the side plate G . These prongs extend into recesses O' in the blocks, the arrangement being such that the upper surface O^2 of the blocks I' will be held against the lower surface O^3 of the vertical wall H , the rear portion of the upper face of the blocks however being recessed to receive the supporting plate member M . It will be noticed that the inner face of the refractory blocks forms a continuation of the inner face of the vertical wall H , the latter being built up to the arch C . However in place of forming a tight connection between the blocks Q and the arch, there is preferably a space Q' left for expansion but an air seal is formed vertically between the sides of the arch and the face R' of the blocks R .

In a furnace constructed as above described, the passage of air from the space above the arch C to the combustion chamber, except through the twyer members I is prevented, and counter drafts avoided. Moreover this advantage is obtained without supporting the arch upon the refractory wall. To permit of the use of the same lower portion of the side plate for furnaces of different height, I preferably form the side plates G in sections G' and G^2 , the latter of which can be of any desired size. Thus by using a higher plate section G^2 , the arch C can be supported further away from the grates, where the length of the furnace makes such arrangement advantageous, while the same standard lower section G' can be used.

For sealing the space above the arch, a floor S is employed. This floor is carried by the beams D in the following manner: Resting on the lower flanges S' of the beams D , are a plurality of inverted T-beams S^2 , spaced apart a distance sufficient to receive a row of refractory blocks or bricks T , the latter having their ends resting on the lower flanges of the T-beams and supported thereby.

Thus the entire arch, air twyers and pro-

tecing vertical wall are so arranged that they can be supported on the side-plate of the fuel magazine, although the invention in certain of its aspects is not limited to supporting these members on the magazine side plate.

One important advantage of the construction is that the flat arch (which is not a true arch but must have a suspensory support) is supported by metallic suspensory members which in turn are supported by metallic members under the influence of the heat of the furnace but protected from the intense heat. It is a well known fact that the co-efficient of expansion of metal and refractory material are quite different so that if the metal were exposed to the same temperature as the refractory the difference in the expansion would cause distortion in the arch. On the other hand if the arch were supported on metal members entirely out of the range of heat the expansion of the refractory material without expansion of the metal would cause distortion. With my construction the metal supporting member is so located that it will expand when the refractory material expands but being at a less temperature. This will compensate for the difference in the co-efficient of expansion with the result that there will be very little distortion.

What I claim as my invention is:

1. In a furnace, the combination with a furnace chamber, of a flat arch therefor having a suspensory support, a side feed stoker including a side plate, and a support for said suspensory support carried by said side plate.

2. In a furnace, the combination with a furnace chamber, of a flat arch therefor, a side feed stoker including a side plate and a support for said flat arch carried by said side plate, said side plate being formed in sections to permit of the furnace arch being supported at any desired height above the bottom of the furnace chamber.

3. In a furnace, the combination with a furnace chamber, of a flat arch therefor having a suspensory support, a side feed stoker including a side plate, a support for said suspensory support carried by said side plate, and a vertical protecting wall also carried by said side plate.

4. In a furnace, the combination with a furnace chamber, of a flat arch therefor having a suspensory support, a side feed stoker including a side plate, and a support for said suspensory support carried by said side plate, twyer members carried by said side plate and a protecting vertical wall also carried by said side plate.

5. In a furnace, the combination with a furnace chamber, of a flat arch therefor, a side feed stoker including a side plate and a support for said flat arch carried by said

- side plate, twyer members carried by said side plate and a protecting vertical wall also carried by said side plate, a portion of said vertical wall being formed of independently removable blocks, and a locking member for holding said blocks in alined position.
6. In a furnace, the combination with a furnace chamber, of a flat arch therefor having a suspensory support, a side plate, a vertical protecting wall carried by said side plate and extending upward to the arch member and arranged to form an air tight joint therewith, and means for supporting said suspensory support arranged adjacent to said side plate and under the influence of the heat transmitted therethrough.
7. In a furnace, the combination with a furnace chamber, of a flat arch therefor having a suspensory support, a side plate, a vertical protecting wall spaced from said side plate, means for supporting said wall from said side plate, said vertical wall having an offset portion forming an air tight joint with said arch, and means for supporting said suspensory support located to be under the influence of heat transmitted through said vertical wall.
8. In a furnace, the combination with a furnace chamber, of a flat arch therefor, a side plate forming a support for said arch, a vertical protecting wall spaced from said side plate, said vertical wall having its inner portion arranged beneath but slightly spaced from a portion of the arch member, and said vertical wall having a portion forming a vertical surface of contact with said arch.
9. In a furnace, the combination with a furnace chamber, of a side feed stoker therefor having a side plate, twyer members carried by said side plate, a flat arch carried by said side plate, a floor above said arch spaced therefrom to leave an air space, and a vertical protecting wall carried by said side plate and spaced therefrom to form an air passage connecting the air above the arch with the twyer members.
10. In a furnace, the combination with a furnace chamber, of a flat arch therefor, a side feed stoker including a side plate, a support for said flat arch carried by said side plate, twyer members carried by said side plate, a vertical protecting wall for said side plate, protecting blocks for said air twyers and means for supporting said blocks from said side plate with the inner wall of the blocks substantially in alinement with said vertical wall.
11. In a furnace, the combination with a furnace chamber, of a flat arch therefor, a side feed stoker including a side plate, and a support for said flat arch carried by said side plate, twyer members carried by said side plate, a protecting wall formed of a plurality of independently removable blocks, prongs on said side plate forming a support for said blocks and a locking member for removably holding said blocks in position on said prongs.
12. In a furnace, the combination with a furnace chamber and a side plate, of twyer members carried by said side plate, inwardly extending ribs carried by said side plate, a plurality of refractory blocks also supported from said side plate, said blocks and ribs having registering recesses, and a locking rod extending into said recesses for removably holding said blocks from lateral displacement.
13. In a furnace, the combination with a furnace chamber, of a sectional side plate having the upper and lower sections, members supported by said lower section, and an inner arch member supported by said upper section.
14. In a furnace, the combination with a furnace chamber, of a flat arch directly over said furnace chamber, said arch comprising a plurality of independently supported members, suspensory supports for said members, and a general support for said arch carried by said side plate.
15. In a furnace, the combination with a furnace chamber, of a flat arch therefor having a suspensory support, a side feed stoker including a side plate, a protecting wall supported from said side plate, and means under the influence of heat radiated from said protecting wall for supporting said suspensory support.
16. In a furnace, the combination with a furnace chamber, of a flat arch therefor, a side feed stoker including a side plate, means for supporting said flat arch from said side plate, and a vertical wall having a plurality of independently removable blocks supported on said side plate, and means for locking said blocks from removal.

In testimony whereof I affix my signature.
EDWIN FITTS.
